UNITED STATES PATENT OFFICE.

ADDISON N. HIMES, OF BERKELEY, CALIFORNIA.

AUTO COMMISSARY AND TABLE.

1,219,101.

Specification of Letters Patent. Patented Mar. 13, 1917.

Application filed March 13, 1916. Serial No. 83,836.

To all whom it may concern:

Be it known that I, ADDISON N. HIMES, a citizen of the United States, residing at Berkeley, in the county of Alameda and State of California, have invented new and useful Improvements in Auto Commissaries and Tables, of which the following is a specification.

This invention relates to an appliance which is designed to be used in conjunction with automobiles and the like to provide convenient accommodations for commissary purposes, said device being capable of extension to form a table and seats which may be used for convenience while eating.

It consists of a rectangular box-like casing having compartment boxes slidable in at one side and having extension leaves hinged to the upper portion in such a manner that they may be turned down and form a closure for each side of the casing, when the compartment boxes are in place. These leaves have hinged to their outer edges strips which are foldable against the inside of the leaves when the device is closed, but which may be opened out and form a support for the leaves, so that the latter are extended in a horizontal position on a level with the top when the device is to be used for a table.

It also comprises details of construction which will be more fully explained by reference to the accompanying drawings, in which—

Figure 1 is a perspective view, looking from above, with the parts open and extended.

Fig. 2 is a similar view, looking from below.

Fig. 3 is a horizontal section of the appliance in closed condition.

A is an exterior rectangular casing, made of convenient size to be placed in front of the rear seat of an automobile, in which position it serves conveniently as a supplemental seat. This casing is provided with drawers 2 which are slidable in and out, and which may be provided with compartments and otherwise arranged to receive such articles as are necessary for commissary purposes, such as knives, forks, spoons, plates, cups, saucers, etc., and also food properly prepared to fit into the boxes.

The sides of the casing, in line with the boxes, form leaves 3 which are hinged to the top in such a manner that they may be opened and stand level therewith. When

closed, these sides cover the whole of the opposite open spaces of the casing and, when locked, secure the contents. When opened up they are supported in this position by strips of material 4 which are hinged to the under part of the covers or leaves 3 at their outer edges. These legs are just long enough to hold the table in a level position and the depth of the table and the width of the leaves are such that the legs will just fold beneath the table, occupying the full width of the leaves. When folded in this manner they lie against the bottom or underside of the table leaves and when not in use to support said leaves, they may be held in position by buttons or fastenings which prevent them from falling down. The leaves may then be closed down and secured at the lower edge to the bottom of the casing, thus sealing it up.

When the leaves are opened out the boxes or compartments may be withdrawn and the contents may be spread upon the table. The boxes are of such length that, when emptied of their contents, they will serve as seats. The table may be placed contiguous to the running-board of an automobile, which will form seats for two persons, while these boxes may be disposed on the opposite side and form seats for two more persons, thus utilizing the device in a very economical manner.

When the meal has been finished, the adjuncts may be again placed in the boxes and the boxes placed in the case, and the legs which support the leaves are folded up against the underside of the leaves, the latter then being closed down and confining the boxes in their places may be locked in any suitable manner.

Handles 6 may be formed in the ends of the case by which it may be conveniently lifted and moved around.

Having thus described my invention, what I claim and desire to secure by Letters Patent is—

1. A commissary attachment for automobiles and the like, comprising a rectangular case having open sides, drawers fitting and slidable in said case, and closures for said open sides consisting of boards hinged at the upper edges and closable over the open sides, said boards having legs hinged to their lower edges and foldable against their inner faces, said legs being capable of extension at right angles with

the boards, with their lower ends resting upon the ground to hold the boards substantially level with the upper side of the case and forming therewith a table.

2. A combination containing case, table and seats, including an exterior case having top, bottom and end members permanently united and open sides, drawer-like boxes 10 slidable into and fitting the interior of the case, and sides hinged to the top of the case adapted to be opened out to form leaves of a table, said sides having legs hinged to their movable edges and foldable against the

lower sides of the leaves to allow them to close and open at right angles so that their 15 free ends will rest upon the ground and support the leaves parallel with the top of the case, said boxes being removable and convertible into seats.

In testimony whereof I have hereunto set 20 my hand in the presence of two subscribing witnesses.

ADDISON N. HIMES.
